[57] CLAIM

The ornamental design for an accessory for a food processor, as shown and described.

DESCRIPTION

FIG. 1 is a front elevational view of an accessory for a food processor showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view thereof.

The accessory according to my new design is a container having a removable lid. When the lid is removed, a food processing unit including a motor, a shaft extending downwardly from the motor and a blade carried at the lower end of the shaft can be mounted on the container so that the blade is disposed adjacent the bottom of the container. The accessory according to my new design can be used alone as a food storage container.
